UNITED STATES PATENT OFFICE.

RODNEY H. MARCHANT, OF OAKLAND, CALIFORNIA.

DESIGN FOR A TOY ANIMAL.

Application filed February 8, 1922. Serial No. 597. Term of patent 3½ years.

To all whom it may concern:

Be it known that I, RODNEY H. MARCHANT, a citizen of the United States, residing at Oakland, in the county of Alameda and State of California, have invented a new, original, and ornamental Design for Toy Animal, of which the following is a specification, reference being had to the accompanying drawing, forming part thereof.

The figure is a perspective view of a toy animal, showing my new design.

I claim:

The ornamental design for a toy animal, as shown.

In testimony whereof I affix my signature.

RODNEY H. MARCHANT.
